ELECTRICAL CIRCUIT BREAKER

Olav Maseng, Evanston, Ill.

Application October 22, 1934, Serial No. 749,330

20 Claims. (Cl. 175—294)

This invention relates to electrical circuit breakers, and an object thereof is to provide an improved means for opening an electric circuit while current is flowing therein and including means for reducing the arcing at the terminals.

A further object of the invention is to provide a circuit breaker of such construction that the gases produced by the arc upon initiating the opening of the circuit are utilized in a manner to provide a high pressure blast across the co-acting surfaces of the terminals.

A further and major feature of the invention resides in the provision of an intermediate contact element positioned between the main contact of the circuit to be interrupted wherein, by first separating a main contact and the intermediate contact, an arc is drawn and thereafter the intermediate contact is separated from the other main contact permitting the gases produced by the first arc to flow under pressure between the said intermediate and second main contacts.

A still further and major object of the invention is to provide a circuit breaker including the main opposed contacts and an intermediate contact positioned therebetween in the arc path and including an auxiliary means for imposing a potential upon the intermediate contact for changing the state of ionization in the arc space and reduce the magnitude of the current flowing across the gap in the final separation of the intermediate contact and a main contact as herein-after described thereby reducing and limiting the duty that the circuit may impose upon the circuit breaker.

It has heretofore been usual to immerse the contact structures of a high voltage circuit breaker in an insulating fluid in which the high dielectric strength thereof is depended upon as a means of interruption of a circuit. Such prior circuit breakers are costly, being of comparatively large size, and further introduce a serious fire and explosion hazard. In my invention, insulating fluids are dispensed with and the arc gases of low dielectric strength, either separately or in combination with an auxiliary potential, are depended upon to reduce the arcing and are utilized for the purpose of interrupting the circuit.

These and other objects and several novel features of the invention are hereinafter more fully described and claimed, and the preferred form of construction of an electrical circuit breaker embodying my invention is shown in the accompanying drawing in which—

Fig. 1 is a longitudinal section of a convenient form of circuit breaker embodying my invention.

Fig. 2 is a partial sectional view showing the contact elements in partly open position.

Fig. 3 is a similar view showing the contacts in the fully open position.

Fig. 4 is a similar view showing an alternative form of an intermediate contact element and its relationship with the main contact or electrode in which it is mounted.

Fig. 5 is a diagrammatic view showing the contact element in the fully open position and the circuit associated therewith for producing a potential at the intermediate contact.

The fundamental form of my improved circuit breaker is shown in Fig. 1. This comprises a body of insulating material 11 but the general form of this member may be varied to suit various characters of installation. This insulating member has a bore 11' which opens through one end of the insulating member and this is closed by the threaded plug 20 and any desired character of packing means 20', preferably cementitious, may be used between the plug and the body to seal the bore 11' at one end. In the bore is the hollow movable electrode or contact member 12 which is attached at one end in any convenient manner to the operating rod 13 which may be moved longitudinally of the axis of the contact 12 by any approved means (not here shown). The contact 12 has an external shoulder 12' that limits the withdrawal movement of the contact element as will be understood from Fig. 3, the shoulder, upon full withdrawal, engaging the packing 20' or base of the plug 20 if the aperture of the packing element through which the electrode extends is of the same diameter as the chamber 11'. Within this contact element 12 is the base of the intermediate contact or electrode 16 which has a tapered base 30 against which the correspondingly tapered edge at the end of the element of the contact 12 engages in the position shown in Fig. 1. To this intermediate contact is secured an insulating body 17 and the outer free end of the insulation element is formed with a collar 21 somewhat greater in diameter. This collar 21 is engaged by the internal shoulder 31 when the contact 12 is withdrawn to the position shown in Fig. 2.

The intermediate electrode 16 has a cone like terminal portion 32 and as shown in Fig. 1, this coned end 32 engages the cone shaped end 33 of the hollow contact 14. This contact element is mounted in a recess 34 in axial alignment with the chamber 11' and having a side outlet to atmosphere indicated at 35. The electrode or contact element 14 has an extension 19 with which

one side 36 of the main circuit is connected while the other side 37 of the main circuit is connected to the contact 12 as diagrammatically shown in Fig. 1. There is a spring 18 engaging a base of the main contact 14 holding the same in the position shown, there being a slight movement of the contact 14 on the axis of the intermediate member and the other main contact 12 to insure contact.

In this fundamental form of the invention, it will therefore be realized that there is a main contact 12, a companion main contact 14 and an intermediate contact 16 in engagement with both the said main contacts when in the closed position shown in Fig. 1. The intermediate contact 16 is pressed to engagement with the contact 14 by means of a spring 18 in the hollow contact 12. Upon starting to open the circuit in this primary construction, the contact 12 is withdrawn by means of the operating rod 13 and associated instrumentalities (not here shown) for causing said movement.

Upon initiating movement of the contact 12 the tapered edge thereof is separated from the coned face 30 of the intermediate contact 16 which is in engagement with the main contact 14. This causes an arc and development of a high pressure gas in the chamber 11' which, during this initial operation, remains closed. On further movement of the member 12 the shoulder 31 engages the enlarged portion 21 on the insulating member withdrawing the coned face 32 out of contact with the coned mouth 33 of the hollow contact 14. This permits the high pressure gas caused by the initial separation of the contacts 12 and 16 to pass through the narrow opening between the portion 32 of the intermediate contact 16 and the coned mouth 33 of the main electrode 14 to atmosphere through the passageways 34 and 35. The gas being partially deionized and cleaned by being forced against the wall of the bore or chamber 11' and narrow passage between the intermediate contact 16 and said wall. These gases are so guided as to pass over the surfaces of the intermediate electrode 16 and the main electrode 14 in intimate contact therewith and tend to quench the incipient arc between these members and maintain a steady high pressure blast over the arc terminals until the circuit is completely interrupted. To insure separation of the contacts 16 and 14, the enlarged end portion is provided for engagement with the shoulder 31 of the contact 12 whereby, prior to completion of movement of the operating rod in separating the contacts, the intermediate electrode or contact 16 is forcibly separated from the contact 14. In fact the intermediate contact may be provided with a longer insulation as indicated at 17' in Fig. 4 so that at the limit of withdrawal movement of the contact 12 the enlarged portion 21 may then be just engaged by the shoulder 31 of the said contact 12.

In the structure shown in Fig. 4, the final separation of the intermediate contacts 16 and 14 is produced by the pressure within the chamber 11'. In this latter case, as the pressure in the chamber decreases, the intermediate contact 16 may again assume the position shown in Fig. 4 without closing the circuit as the said electrode is supported in the main electrode 12 by the insulation rod or element 17.

In the form or forms of the invention so far described, the interruption of the arc is solely by the quenching effect of the gases developed in the chamber 11' and it will be evident from the

description above given, that various objects of the invention are attained by a structure that is of simple character and comparatively compact in form and without the use of insulating fluids heretofore commonly used in this art where high voltage circuits carrying current of high amperage are to be broken or interrupted.

The utility of the device as heretofore described, particularly for circuits carrying large currents may be enhanced as indicated in Fig. 5 which, in association with the parts heretofore described, includes an additive feature comprising an auxiliary circuit energized by the main circuit in such manner that a potential or impulse is impressed upon the intermediate electrode 16 subsequent to the separation of the contact members when the circuit is being interrupted. This potential will cause the main current to be diverted to the secondary circuit in which, due to the impedance included, the current flow will be limited to a low value which may be readily interrupted by the remaining gap between the intermediate electrode 16 and the main electrode 14.

It is therefore a function of the auxiliary circuit 22', 23, 24, 16, 37, 22' to constitute an auxiliary circuit useful in impressing a positive potential on the auxiliary contact 16.

The auxiliary circuit includes a current transformer 22' having its primary winding in the main circuit 37. The secondary winding of the transformer also has one end connected to the main circuit at 40 while the other end is connected to the impedance 23 and lead 24 extending through the breaker structure to the intermediate contact member 16. When the circuit breaker shown is opened by withdrawal of the electrode 12, the initial arc will be produced as heretofore described and as the intermediate electrode is being withdrawn toward the position shown in Fig. 3, current will be forced to flow in the circuit from terminal 18, contact member 14 through the arc existing between contact members 14 and 16, the line 24, impedance 23 and the secondary of the current transformer 22 to the main circuit 37 which, under this condition, is dead ended due to the fact that the terminal contact element or electrode 12 is disconnected from the intermediate electrode 16. Due to the impedance in this new current path, the magnitude of current permitted to flow is limited to a desired low value such as can be readily interrupted by a gap between the intermediate electrode 16 and main electrode 14 which, at the time of interruption, is swept by gases under pressure produced by the initial movement of the electrode 12.

In the form of the invention shown in Fig. 1 and in the same structure associated with the auxiliary circuit, there is, on initiation of the opening of the circuit, a gas pressure produced in the chamber 11' which, upon movement of the intermediate electrode 16 out of contact with the electrode 14, passes through the gap tending to quench the arc. By use of the auxiliary circuit, the current flowing at the time of breaking the contact of the intermediate electrode 16 with the main electrode 14 is reduced to a low value permitting a more ready separation and less arcing than is the case when the auxiliary circuit is not utilized. Thus the auxiliary circuit is adaptable for use under differing conditions or structural form and relationship of circuit breaker parts, the structure of Fig. 1 being illustrative of a convenient means for positioning the inter-

mediate contact element in the arc path between the main contact members. In its simplest form, the auxiliary circuit involves the application of a potential to a member positioned or positionable in the arc path between the main contact members of a breaker and in effect provides a high impedance path to the current flow whereby the magnitude of the current flow in the main circuit prior to interruption is reduced.

10 Consequently the use of an auxiliary circuit will increase what may be termed the "interrupting" capacity of a particular circuit breaker.

The breaker as heretofore described in detail may be varied in structure particularly for the 15 adaptation of the breaker for various characters of installation and the auxiliary circuit described for producing a potential at the intermediate electrode positioned or positionable in the arc path, may be varied in impedance, capacitance 20 etc., to thereby adapt the same for use with circuit breakers of different current capacity.

It is obvious that various changes may be made in structure and in the auxiliary circuit without departing from the spirit and scope of the invention as set forth in the appended claims. The 25 impedance 23 may be a separate element as shown or may be incorporated in the transformer 22 and while I have shown a capacitance 28 for shunting the secondary transformer, it is not 30 essential but appears to improve the effectiveness of the circuit. The housing 11 may be of any desired construction or form and the material utilized in the contact supporting parts may be 35 varied in respect to the gas generating and arc resisting qualities, depending upon the duty and character of the circuit with which my improved circuit breaker is usable.

It is evident from the foregoing that my improved circuit breaker is of a comparatively 40 small and compact form, materially less expensive than the usual circuit breakers of the same capacity utilizing an insulating liquid and that the various objects and features of the invention are attained by the structures described.

45 Having thus fully described my invention, its utility and mode of operation, what I claim and desire to secure by Letters Patent of the United States is—

1. A circuit breaker comprising a housing of 50 insulating material having a chamber extending longitudinally thereof and having an opening through the housing wall to atmosphere, a pair of main contact members in the housing, one of the said contacts being adjacent the said opening and having a passageway therethrough, an intermediate contact positioned in the arc path between the said main contacts and normally in engagement therewith thereby closing the said passageway in the one main contact, said main 55 contact being spring supported, means for withdrawing the other main contact from engagement with the intermediate contact thereby drawing an arc in the chamber and producing a high gas pressure therein, and means whereby, in withdrawal of the said other main contact, the intermediate contact is in sequence withdrawn from engagement with the main contact having the passageway thereby opening the chamber to atmosphere and causing a passage of the gases 60 across the normally contacting surfaces of the intermediate contact and the said main contact having the passageway, and means for imposing a positive potential at the intermediate contact during the opening of the circuit breaker.

75 2. A circuit breaker comprising a housing of

insulating material having a chamber, a pair of main contact elements therein forming the terminals in an electric circuit, an intermediate contact element positioned between and normally engaged by the main contact, means for withdrawing one of the main contacts from engagement with the intermediate contact thereby producing an arc in the said chamber, the chamber being normally closed to atmosphere by the intermediate contact and the drawn arc generating 10 a high pressure gas within the chamber, and means whereby, in the withdrawal of the said main contact, the intermediate contact is in sequence withdrawn from engagement with the other main contact and opening the chamber to 15 atmosphere thereby permitting the passage of the high pressure gases across the contacting surfaces of the said intermediate contact and said other main contact, and means for imposing a positive potential at the intermediate contact 20 during the opening of the circuit breaker.

3. A circuit breaker comprising a housing formed of insulating material having a chamber therein provided with a passageway to atmosphere, a pair of main contact elements in the 25 chamber of the housing forming the terminals in a circuit, one of the main contacts having an aperture and being positioned at the junction of the chamber and passageway, an intermediate contact element between and normally in contact with the main contacts and closing the aperture in the apertured main contact, withdrawal of the other main contact from engagement with the intermediate contact producing 30 an arc and generating high pressure within the chamber, and means whereby, on withdrawal of the said other main contact, the intermediate contact is thereby in sequence withdrawn from engagement with the apertured main contact 35 thereby opening the chamber to atmosphere through the apertured main contact and causing the high pressure gases to sweep the contacting faces of the apertured and intermediate contact elements, and means for imposing a positive potential at the intermediate contact during 40 the opening of the circuit breaker.

4. A circuit breaker comprising an insulating housing having a chamber therein, a circuit including a pair of main contact elements positioned in the chamber, an intermediate contact 50 element normally in engagement with the main contact, the chamber having a passageway to atmosphere through one of the main contacts normally closed by the intermediate contact, the arrangement providing that, on withdrawal of the other main contact from engagement with the intermediate contact, an arc is drawn and high pressure gases produced in the chamber and on withdrawal of the intermediate contact 55 in sequence from engagement with the first named main contact, the arc path between the said intermediate contact and the first said main contact is swept by the high pressure gases flowing through the passageway thereby quenching the arc, and means for imposing a positive potential at the intermediate contact during the opening of the circuit breaker.

5. A circuit breaker comprising a housing formed of insulating material and having a 70 chamber therein opening at one end to atmosphere, a circuit having a pair of main contact elements movable in the chamber, one main contact being at the said chamber end and having an opening therethrough, the other main contact 75

- tact being movable in the opposite end of the chamber, a spring for said first named main contact tending to move the same toward the other, an intermediate contact element normally 5 engaging the first named main contact and closing the opening therethrough, means for withdrawing the second main contact from engagement with the intermediate contact thereby producing an arc and generating a high gas pressure within the chamber, said withdrawing means including a means for sequentially withdrawing the intermediate contact from engagement with the apertured main contact thereby permitting high pressure gases to sweep the contacting surfaces of the said intermediate and apertured contacts to thereby finally interrupt the circuit, and means for imposing a positive potential at the intermediate contact during the opening of the circuit breaker.
- 10 6. A circuit breaker having main separable contact members providing a circuit terminal, an intermediate contact element therebetween normally engaged thereby, a housing formed of insulating material and having a chamber opening to atmosphere in which the several contact elements are operatively positioned, the said intermediate contact being positioned in the path of the arc when the said main contact members are separated, the arrangement of the parts being such that the drawn arc upon relative separation of the main contacts produces a high pressure gas in the chamber and upon separation of the intermediate contact and the other main contact, the chamber is opened to atmosphere permitting the gases under pressure to flow between the contacting faces of the intermediate and last named contacts, and means for imposing a positive potential at the intermediate contact during the opening of the circuit breaker.
- 15 7. A circuit breaker having main separable contact members providing a circuit terminal, an intermediate contact element therebetween normally engaged thereby, a housing formed of insulating material and having a chamber, the chamber having a passageway to atmosphere normally closed by the intermediate contact when the circuit is closed through the breaker, and means for withdrawing one of the main contacts from engagement with the intermediate contact, the arrangement being such that, on separating the other contact in sequence from engagement with the intermediate contact, the arc path therebetween is swept by the high pressure gases thereby quenching the arc, and means for imposing a positive potential at the intermediate contact during the opening of the circuit breaker.
- 20 8. A circuit breaker having main separable contact members providing a circuit terminal, an intermediate contact element therebetween normally engaged thereby, a housing formed of insulating material and having a chamber, the chamber having a passageway to atmosphere normally closed by the intermediate contact when the circuit is closed through the breaker, and means for withdrawing one of the main contacts from engagement with the intermediate contact, the arrangement being such that, on separating the other contact in sequence from engagement with the intermediate contact, the arc path therebetween is swept by the high pressure gases thereby quenching the arc, and an auxiliary circuit energized by the main circuit and imposing a potential at the intermediate contact positive to the surrounding arc space where-
- 25 by the magnitude of current flowing in the main circuit is reduced during the opening operation of the circuit breaker.
9. A circuit breaker having main separable contact members providing a circuit terminal, an intermediate contact element therebetween normally engaged thereby, a housing formed of insulating material and having a chamber, the chamber having a passageway to atmosphere normally closed by the intermediate contact when the circuit is closed through the breaker, and means for withdrawing one of the main contacts from engagement with the intermediate contact, the arrangement being such that, on separating the other contact in sequence from engagement with the intermediate contact, the arc path therebetween is swept by the high pressure gases thereby quenching the arc, and an auxiliary circuit electrically connecting the intermediate contact member to the main circuit and including the secondary winding of a current transformer, the primary of which is connected in the main circuit whereby during the opening of the circuit breaker a potential is imposed at the intermediate contact positive to the surrounding arc space and the magnitude of current flowing in the main circuit is reduced.
- 30 10. A circuit breaker having main separable contact members providing a circuit terminal, an intermediate contact element therebetween normally engaged thereby, a housing formed of insulating material and having a chamber, the chamber having a passageway to atmosphere normally closed by the intermediate contact when the circuit is closed through the breaker, and means for withdrawing one of the main contacts from engagement with the intermediate contact, the arrangement being such that, on separating the other contact in sequence from engagement with the intermediate contact, the arc path therebetween is swept by the high pressure gases thereby quenching the arc, and an auxiliary circuit energized by the main circuit and imposing a potential at the intermediate contact positive to the surrounding arc space whereby the magnitude of current flowing in the main circuit is reduced at the time the intermediate contact is separated from the last named main contact, said auxiliary circuit electrically connecting the intermediate contact member in the main circuit and including the secondary of a current transformer, the primary of which is connected in the main circuit, and a capacitance shunting the said secondary winding of the transformer.
- 35 11. In a circuit breaker, a chambered housing, a circuit having main separable contact members in the chamber, an intermediate contact axially disposed therebetween and normally in engagement therewith, means for separating the intermediate and main contact members in such manner that during interruption of the main circuit, the intermediate contact member provides an intermediate arc terminal between the main contact members, the arrangement providing that, during actuation of the contact members in interrupting the circuit, gas is first generated in the chamber and then passes to atmosphere between the intermediate contact element and one of the main contacts when separated, and an auxiliary circuit electrically connecting the intermediate contact member to the main circuit to thereby impose a positive potential upon the intermediate contact during separation of the contacts and reducing the intensity of the arc to
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

be quenched by the flow of gases from the chamber.

12. An electric circuit breaker comprising a housing of insulating material having a chamber, a circuit having main separable contacts providing terminals and an intermediate contact axially disposed therebetween, said contact members being disposed in the chamber and the chamber having an opening to atmosphere closed by the intermediate contact, means for moving the intermediate contact and opening the chamber to the passage of gases therefrom, said means for moving the intermediate contact member being of such character that, during interruption of the circuit, the intermediate contact forms an intermediate arc terminal between the said main contact members, an auxiliary circuit electrically connected with the intermediate contact member and the main circuit, and an impedance in the auxiliary circuit for limiting the magnitude of current flow in the main circuit, said auxiliary circuit providing means for imposing a potential upon the intermediate contact member during separation of the main contacts that is substantially positive to the surrounding arc space thereby diverting and reducing the magnitude of the subsequent current flow in the main circuit and facilitating interruption thereof.
13. A circuit breaker comprising an insulating housing having a chamber and a main circuit including a pair of contact members positioned in the chamber, an intermediate contact member normally in engagement with the main contacts, the chamber having a passageway to atmosphere and one of the main contacts having an opening leading thereto closed by the intermediate contact when the circuit is closed through the breaker, an auxiliary circuit having a source adapted to impose a potential upon the intermediate contact substantially positive to the arc space surrounding the same whereby, when separated from the other main contact and the passageway opened, the magnitude of current flowing in the main circuit is reduced, and the gases generated in the chamber pass between the intermediate contact and the last named main contact to the passageway.

14. A circuit breaker comprising an insulating housing having a chamber therein, a main circuit including a pair of main contact members positioned in the chamber, an intermediate contact member normally in contact with the main contacts, the chamber having a passageway to atmosphere normally closed by the intermediate contact when the circuit is closed through the breaker, an auxiliary circuit energized by the main circuit to impose a potential upon the intermediate contact substantially positive to the arc space immediately surrounding the same whereby, when separated from the other main contact and the passageway opened, the magnitude of current flowing in the main circuit is reduced, and the gases generated in the chamber pass between the intermediate contact and the last named main contact to the passageway.

15. In an electrical circuit breaker, a pair of main separable contact members forming the terminals of the circuit to be interrupted, an additional contact member, means supporting the said additional contact member in the arc path between the said main separable contact mem-

bers, and an auxiliary circuit electrically connecting the additional contact member to the main circuit, the said auxiliary circuit including a source imposing a potential upon the said additional contact during separation of the main contact members that is positive to the space surrounding the said additional contact member.

16. In an electrical circuit breaker for interruption of a circuit, a pair of main separable contact members forming the terminals of the circuit to be interrupted, an additional contact member, insulating means supporting the said additional contact member axially between the said main contact members, an auxiliary circuit electrically connecting the additional contact member to the main circuit, an impedance in the auxiliary circuit, and a transformer, the secondary winding thereof being in the auxiliary circuit and the primary of which is energized from the main circuit whereby during the opening of the main circuit a positive potential is imposed on the additional electrode and current flowing in the circuit being interrupted is diverted and reduced in magnitude thereby facilitating interruption.

17. In an electrical circuit breaker for interruption of a circuit, a pair of main separable contact members forming the terminals of the circuit to be interrupted, an additional contact member, insulating means supporting the said additional contact member axially between the said main contact members, an auxiliary circuit electrically connecting the additional contact member to the main circuit, an impedance in the auxiliary circuit, a transformer, the secondary winding thereof being in the auxiliary circuit and the primary winding being energized from the main circuit, and a capacitance shunting the said secondary winding whereby during opening of the main circuit current flow is diverted and reduced in magnitude thereby facilitating interruption.

18. In an electrical circuit breaker, a pair of axially aligned main contact elements forming the terminals of a circuit to be interrupted, an intermediate member, means positioning the intermediate member axially and in the arc path between the main contact members, and an auxiliary circuit electrically connecting the intermediate member to the main circuit, said auxiliary circuit including an impedance, and the secondary winding of a current transformer, the primary winding of which is connected in the main circuit.

19. In an electrical circuit breaker having main contact elements forming terminals of a circuit to be interrupted, an intermediate member positioned in the arc path between said contact elements, and an auxiliary circuit electrically connecting the intermediate member to the main circuit, the auxiliary circuit including a source imposing a potential on the intermediate member substantially positive to the space surrounding the same.

20. In an electrical circuit breaker having separable contact members, an auxiliary circuit connecting one of the contact members to a point in the path of an arc drawn therebetween, said auxiliary circuit including a source for impressing a potential substantially positive to the arc space at the said point in the arc path.
